UNITED STATES PATENT OFFICE.

MORRIS A. HEIMANN, OF ST. LOUIS, MISSOURI.

DESIGN FOR A MANTLE-HOLDER.

SPECIFICATION forming part of Design No. 34,504, dated May 14, 1901.

Application filed April 6, 1901. Serial No. 54,751. Term of patent 7 years.

To all whom it may concern:

Be it known that I, MORRIS A. HEIMANN, a citizen of the United States, residing at St. Louis, in the State of Missouri, have invented and produced a new and original Design for a Mantle-Holder, of which the following is a specification, reference being had therein to the accompanying drawings.

My invention relates to a new and original design for a mantle-holder.

Figure 1 is a front view of my design. Fig. 2 is a side view of the same, and Fig. 3 is a top plan view.

As shown in the drawings, the leading or material feature of my design consists of a single strand of wire 1, its one end formed into a ring 2 and bent upwardly at 3. The

strand is extended upwardly and bent at 4, extending partially downward, forming a hook 5. It is again bent at 6 and extends downwardly and bent around the ring 2, forming an eye 7.

Having fully described my invention, what I claim as new, and desire to secure by Letters Patent, is—

The design for a mantle-holder as herein shown and described.

In testimony whereof I affix my signature in presence of two witnesses.

MORRIS A. HEIMANN.
